UNITED STATES PATENT OFFICE.

CLARENCE W. BENNETT, OF NEW YORK, N. Y., ASSIGNOR TO ARDEN MANUFACTURING CORPORATION, OF NEW YORK, N. Y., A CORPORATION OF NEW YORK.

DESIGN FOR A TOY AUTOMOBILE.

53,978.

Specification for Design.

Patented Nov. 4, 1919.

Application filed May 15, 1919. Serial No. 297,406. Term of patent 7 years.

To all whom it may concern:

Be it known that I, CLARENCE W. BENNETT, a citizen of the United States, residing at New York city, New York, have invented a new, original, and ornamental Design for Toy Automobiles, of which the following is a specification, reference being had to the accompanying drawing, forming a part thereof.

The figure is a perspective view of a toy automobile showing my new design.

I claim:—

The ornamental design for a toy automobile, as shown.

CLARENCE W. BENNETT.
